PROCESS AND MECHANISM FOR FORMING HOLLOW WARE ARTICLES

Application filed August 25, 1930. Serial No. 477,519.

This invention relates to an improved process and mechanism for forming hollow ware articles from paper pulp or the like, and it has for its principal object to provide a novel method of treating hollow ware articles formed from paper pulp whereby they may be quickly and evenly formed about a shaping mold, economically and effectively freed of moisture and conditioned to permit of convenient handling and further drying and finishing.

Another object of the invention resides in that step in the process which consists in a rolling and pressing treatment of the article while it is on the mold to make the walls substantially compact and whereby a smooth and finished appearance is given the article and whereby it is loosened for easy removal from the mold.

Other objects of the invention reside in the various novel steps of forming, drying, pressing and removing the article as will be recited in the following description.

Still further objects reside in the details of construction of the various parts of the machine for carrying out the process and in their mode of operation.

In accomplishing these objects, I have provided the improved details of construction, the preferred forms of which are illustrated in the accompanying drawings wherein—

Fig. 1 is a side elevation of the mechanical apparatus utilized in carrying out the various steps of the present invention.

Fig. 2 is a vertical section substantially on the line 2—2 in Fig. 1.

Fig. 3 is a detail view in rear elevation of the presser rolls and operative parts with the forming mold shown therebetween.

Fig. 4 is an enlarged view of portions of the pressing apparatus partly in longitudinal section.

Fig. 5 is a fragmentary section of the rotative suction chest and one of the forming molds operatively connected therewith.

In carrying out the process according to the present invention for the formation of hollow ware articles from paper pulp, I first cause the deposit of a layer of pulp upon the exterior surface of the walls of a perforated,

interior mold, about which the article is formed. This is effected by applying suction to the interior of the mold while it is immersed in a vat of hydrated pulp, and this suction is maintained upon the article to be formed, hereinafter referred to as the "container", for a period of time sufficient to exhaust or withdraw the major portion of the contained moisture or water and to somewhat solidify the walls of the container. Then, the mold with the pulp deposit adhering to its exterior cylindrical walls and to its bottom or end wall is passed between opposed, perforated pressing devices which bear against the exterior cylindrical surface of the deposit with the suction maintained thereon while the container is subjected to a rolling action under pressure to remove the major part of contained water and compresses the container walls.

Prior to final pressing, the suction is cut off and this permits of a stretching or loosening of the walls of the container from the mold to provide for easy removal.

When the rolling and dehydrating action is finished, the pressure devices are retracted, the suction on the interior of the mold being removed and the bottom pressure is drawn away from the mold to pull the container by suction off the mold whereupon it is dislodged in such condition that a relatively slight amount of drying by evaporation renders it ready for use.

Referring more in detail to the drawings— Fig. 1 designates a supporting frame in which is rotatively mounted an annular, hollow suction chest 11 connected by hollow spokes 12 to a solid axle 13 on one side and to a hollow axle 15 on the other side. The hollow axle is communicatively connected to the several spokes and to a suction pipe 16 through which suction is continuously maintained within the chest.

Devices to intermittently rotate the chest are provided and consist of a wheel 17 keyed to the solid axle 13 having a suitable number of transverse sockets 18 in its periphery according to the number of intermittent movements to be made in the rotary travel of the chest, and which sockets are adapted to re-

ceive a pintle 20 on a wheel 21 driven at a constant speed through geared connection with a driven shaft 22.

A plurality of hollow mandrels 23 extend radially outward from said chest with which they are in communication and are each controlled by three-way valves 25 arranged to close said communication and open the outer ends of said mandrels to the atmosphere when suitably actuated through arm 26. 27 indicates a mold, see Fig. 5, rotatively supported on the outer end of each said mandrel which may be of any suitable size or shape to correspond to the article or container to be formed. Said molds are hollow and perforated in its circumferential wall 28 and bottom wall 29 and suction is communicated thereto through the outer open end of its mandrel.

31 indicates a vat of hydrated pulp material suited to form the said hollow containers. The chest in its rotation, as indicated by the arrow in Fig. 1, causes the molds 27 to be immersed in said pulp, the respective valve 25 thereof being previously opened through contact of the arm 26 with a cam plate 24 to close the vent to the atmosphere and establish communication with the suction in the chest, and thereupon a layer of pulp is caused to form about the side and bottom walls of the mold. The intermittent movement of the chest carries the mold in its turn with the pulp container bodies 32 thereon for a considerable period of its travel with the suction acting thereon whereby a large part of the water in the pulp is removed and the containers are thus prepared for the final and finishing portion of their treatment.

Numerals 33 and 35 indicate cylindrical presser rolls keyed to the spindles 36 and 37, respectively, and are driven by sprocket chains 38 and 40 passing about sprocket wheels 41 and 42, respectively, mounted on wheels 43 and 45 keyed on said drive shaft 22. Said spindles are rotatively supported at their opposite ends in pairs of dependent swingable arms 46 and 47, respectively, supported at their upper ends on hangers 48 of the drive shaft. Said pairs of arms 46 and 47 are arranged to be yieldingly pressed together and to contact on opposite sides of the mold 27 by means of coil springs 50 mounted on a rod 51 exteriorly of the respective said arms. At predetermined periods when the pressure and rolling operations upon the mold are completed the arms are separated and the mold released from the rolls by means of a toggle-spreader 52 actuated downwardly through a rod 53 engageable at its upper end by a cam 55 on said shaft 22 and at other times held in its upper inoperative position by a spring 56.

A bottom-forming presser 57 of circular configuration having a hollow interior, see

Fig. 4, and a perforated end wall 58 of the diameter of the container to be formed is mounted to rotate freely on a tubular mandrel 60 through which suction is applied through pipe 61 which suction may be cut off through a three-way valve 62 having an operating arm 63. Said mandrel 60 is arranged to reciprocate in sliding bearing 65 by means of an oscillating arm 67 pivoted at 68 and controlled in its vibratory movements by a drum 70 having a cam-groove 71.

In the intermittent rotation of the chest the periods of rest coincide with a horizontal position of the mandrels and the containers thereon between the rolls 33 and 35. Immediately after the respective mold is so positioned the toggle-spreader is released and said rolls contact with the exterior side walls of the container. Said rolls are under constant rotation and with the pressure exerted through springs 50 compact the fibrous material and squeeze out the moisture. Prior to the completion of the pressing action of the rolls the suction in said mold being acted upon is cut off by the tripper 72 acting upon arm 26 of the valve 25 which opens said mold to the atmosphere. Said tripper is actuated through a bell-crank 73 controlled by a rod 74 from a cam 75 on the drive shaft 22. The final action of the rolls upon the container with the interior suction cut off causes the side walls thereof to be slightly stretched so that it may later be readily removed.

Said rolls are preferably several times the diameter of the container so that a considerable number of rotations will be given the container while the rolls are being rotated at a speed and to the number of rotations determined by the ratio of the sprocket wheels 41 and 42 to those numbered 43 and 45, respectively. Simultaneously, the presser 57 is advanced and contacts with the bottom of the container and is rotated therewith on its mandrel. Suction is applied through the perforated end of the presser which together with the suction within the mold 27 will remove considerable moisture from the container bottom. Upon the termination of the action of the rolls on the container and upon their opening movements the presser 57 is retracted pulling the container off the mold by suction. At the end of the rearward travel of the presser 57 a slide arm 76 connected at one end therewith and having a slot 77 at its opposite end in which the arm 63 of the valve 62 is engaged causes the closing of said valve and opening the presser to the atmosphere so that the suction is removed from the container and allows the latter to drop in a chute 78 wherefrom it may be removed to a drying room or convenient place for the final removal of moisture. When the mandrel 60 is moved forwardly again to engage a new container the valve 62 is closed

to the atmosphere and opened to the suction in a well understood manner.

It will be understood that the above apparatus is illustrative merely and that various ways and means may be utilized to carry out the details of my improved process and I do not intend to confine myself to such details of construction except as called for in the annexed claims.

10 Having thus described my invention, what I claim as new therein and desire to secure by Letters Patent, is:

1. The process of making hollow articles from pulp, consisting in forming a deposit 15 of pulp upon the exterior of a perforated mold through interior suction in said mold while immersed in a mass of hydrated pulp, pressing the exterior side wall of said deposit during the maintenance of pressure, 20 simultaneously pressing the bottom of said deposit with exteriorly applied suction, and the removal of the molded article through suction and retraction off said mold.

2. The process of making hollow articles 25 from pulp, consisting in forming a deposit of pulp upon the exterior of a perforated mold through interior suction, applying pressure rolls to the exterior of said deposit, simultaneously applying pressure and exterior 30 suction to the bottom of said deposit, cutting off the interior suction, and removing said article through the continued application of said bottom suction.

3. The process of making hollow containers 35 from pulp, consisting in forming a deposit of pulp upon the exterior of a perforated mold through internally applied suction while immersed in a mass of hydrated pulp, squeezing by rolling pressure the outer circumferential surface of said deposit under 40 continued suction cutting off said suction prior to the completion of said squeezing action applying pressure and suction exteriorly to the bottom of said deposit, releasing 45 the side wall of the deposit from said squeezing action, and removing said container from the mold.

4. The process of making hollow containers 50 from pulp, consisting in forming a deposit of pulp upon the exterior of a perforated mold through internally applied suction while immersed in a mass of hydrated pulp, squeezing by rolling pressure the outer circumferential side wall of said deposit under 55 continued suction, cutting off said suction prior to the completion of said squeezing action, applying pressure and suction exteriorly to the bottom of said deposit, relieving the side wall of the deposit from said squeezing 60 action, and pulling off said container from the mold through said externally applied suction.

5. The process of making hollow containers 65 from pulp, consisting in forming a deposit of pulp upon the exterior of a perforated mold

through internally applied suction while immersed in a mass of hydrated pulp, squeezing by rolling pressure the outer circumferential side wall of said deposit under continued suction, cutting off said suction prior to the completion of said squeezing action, applying pressure and suction exteriorly to the bottom of said deposit, relieving the side wall of the deposit from said squeezing action, pulling off said container from the mold through said externally applied suction, and cutting off said external suction to release said container.

6. The process of making hollow containers 70 from pulp, consisting in forming by interior suction a deposit of pulp upon the exterior surfaces of a plurality of hollow perforated molds successively by immersing said molds in a mass of hydrated pulp, each mold and deposit thereon being in turn brought to rest in a horizontal position whereat external squeezing by rolling pressure is applied oppositely upon the side wall of said deposit, cutting off said suction prior to the completion of said squeezing action, applying pressure 75 and suction externally to the bottom of said deposit, relieving the side wall from said squeezing action, pulling off the container from the mold through said externally applied suction, advancing said released mold to bring another into operative relation to said squeezing devices, advancing said relieved mold for immersion to receive a fresh deposit of pulp, and opening said mold to said interior suction.

7. In a machine of the character described, a container for hydrated pulp, a plurality of hollow perforated molds, a carrier for said molds, means for advancing the carrier to successively position the molds within said container, means for causing interior suction 100 to be applied to the molds while in the container to cause the deposit of a layer of hydrated pulp thereon, means with which the said molds may be pressed into rolling contact while suction is maintained to dehydrate the deposited layer of pulp, and means for cutting off the suction prior to completion of the rolling process to cause loosening of the deposit from the mold.

8. In a machine of the character described, a container for hydrated pulp, a plurality of hollow perforated molds, a carrier for said molds, means for advancing the carrier to successively position the molds within said container, means for causing interior suction 105 to be applied to the molds while in the container to cause the deposit of a layer of hydrated pulp thereon, means with which the said molds may be pressed into rolling contact while suction is maintained to dehydrate the deposited layer of pulp, means for cutting off the suction prior to completion of the rolling process to cause loosening of the deposit from the mold, and means for effecting 110 the removal of the deposit from the mold.

9. A machine of the character described, comprising a vat for hydrated pulp, a rotatable suction chest, a plurality of hollow, rotatable molds mounted by said suction chest and having connection therewith, valves in said connections for controlling the application of suction to the molds, means for intermittently advancing the chest to successively position the molds within the vat, means for actuating the valves to cause suction to be applied to the molds while in the vat to cause the deposit of a layer of hydrated pulp thereon, rolling means adapted to be brought into pressing contact with the deposited layer to dehydrate it, and means adapted to withdraw, by suction, the formed article from the mold.
